UNITED STATES PATENT OFFICE

AUGUST E. GIESE, JR., OF GARY, INDIANA

TAPPING HOLE DRILLING APPARATUS FOR BLAST FURNACES

Application filed April 9, 1932. Serial No. 604,186.

This invention relates to an improved apparatus and machine to be used for drilling an opening through a blast furnace tapping hole for the discharge of the molten metal from the furnace.

In the operation of blast furnaces, the tapping hole is plugged or filled with clay after a casting run, the clay being usually forced 10 into the hole by means of a mud gun. Before the next casting run, an opening must be formed through the baked and hardened clay for discharge of the molten metal, and such opening usually slants downwardly towards the bottom of the furnace in order that 15 all of the molten metal in the furnace may be run off. A splasher plate must therefore be laid over the runner trough to receive the impact of the discharging molten metal and 20 to deflect it back into the runner trough.

Heretofore, laborious, expensive, and dangerous means and procedures have been used for opening up the tapping hole or placing 25 the splasher plate in position, the procedures requiring the men to operate very close to the runner trough and to the tapping hole outlet. Furthermore, with the procedures 30 heretofore resorted to, there was no assurance of accuracy in the directioning of the opening through the tapping hole clay filler, the directioning of the drilling means or 35 poking implements depending merely upon the judgment and accuracy of the operators.

The important object of my invention is 40 therefore to provide apparatus and machinery which can be safely and accurately controlled from points remote from the runner trough or the tapping hole to quickly and 45 accurately lay the splasher plate in place and to then with power and accuracy drill a discharge opening through the clay filling 50 in the tapping hole and to penetrate any so called metal skull at the inner end of the 55 tapping hole.

A further object is to provide an arrangement in which the splasher plate controlling mechanism and the drill adjusting, controlling and operating mechanism are supported 60 on a boom which may be swung by suitable power to position and locate the apparatus for operation or to remove it away from the runner trough and from the tapping hole after a service operation thereof, together 65 with power driving elements for the operat-

ing parts of the apparatus, all controllable from a remote point.

The various features, construction and arrangement and operation of my invention are incorporated in the structure disclosed 60 on the drawings, in which drawings:

Figure 1 is a side elevation of the apparatus in operating position relative to a furnace of which part of the front wall and 65 the runner trough are shown in cross section.

Figure 2 is an enlarged side elevation, partly in section, on a vertical median plane;

Figure 3 is a side elevation of the supporting boom structure and with the apparatus 70 thereon in section on plane III—III of Figure 2.

Figure 4 shows the application of a detachable bit in the end of the drill;

Figure 5 shows the application of a poking bar in the drill spindle socket; and 75

Figure 6 is a diagram showing the remote control for the motors and other operating devices.

I have shown part of the front wall of a furnace F having the tapping hole 10 in front of which is the runner trough structure 11 for receiving the molten metal. On the floor 12, at one side of the runner trough, is secured a base 13 from which rises a post 14 which receives a sleeve or hub 15 supported on the post at its lower end by a suitable thrust bearing 16 and supported and guided at its upper end by a guide bearing 17. Secured to the top and extending laterally from the sleeve 15 is the boom 18, the boom being shown of rectangular cross section and built up of side channels 19 and top and bottom plates 20 and 21. Extending upwardly through the boom from the post 14 and rigidly secured to the post is the shaft 22 which at its outer end has secured thereto a bevel gear 23. Mounted on top of the boom is an electric motor 24 whose shaft is connected by a coupling 25 with a speed reducing structure indicated by 26 the outlet shaft of which carries a beveled pinion 27 which engages the beveled gear 23, the gear 23 forming a track for the pinion 27 so that, when the motor 24 is running, the boom 18 will be swung in one direction or the other, depending upon the direction of rotation of the motor. The switches or other means (not shown) for controlling the circuit of the motor may be at some point remote from the furnace.

After a casting run of the furnace, the clay

in the tapping hole 10 is worn and carried away by the outflowing metal, and at the end of a casting run, the tapping hole is refilled with clay by means of a clay gun and, before 5 another casting run can be made, an outlet opening must be drilled through the baked and hardened clay, such opening usually inclining downwardly toward the bottom of the furnace. After the opening has been 10 formed, the molten metal will flow out through the opening and a suitable splash plate must be laid over the runner trough for receiving the molten metal stream and deflecting it back into the runner trough. I 15 have shown a splash plate P which may be in the form of a rectangular metal frame having material, such as fire brick 28 secured to its under side against which the molten metal impacts, the frame P being 20 provided with an apertured lug or eye 29 by means of which the plate may be lifted and transported.

The supporting and carrier structure A for the splasher plate comprises the rectangular frame part or head 30 which receives the end of the rectangular boom 18, side walls 31 and 32 depending from the head and being connected at their front ends by a cross wall 33 and inwardly of said walls 30 by an intermediate cross wall 34. Between the walls 33 and 34, the horizontal wall 35 extends between the side walls 31 and 32 and forms a support for a suitable motor for controlling a hook structure 36 for carrying the 35 splasher plate P. Any suitable type of motor may be used. I have shown a motor operable by fluid pressure and comprising a cylinder 37 within which a piston 38 is movable and connected with a piston rod 39 40 which extends through the opposite end walls of the cylinder, pipes 40 and 41 being connected with the opposite ends of the cylinder for the application of fluid under pressure to the desired side of the piston. The 45 cylinder is secured on the cross wall 35 in any suitable manner.

The shank of the hook structure shown has the forwardly extending end 42 terminating in the upward extension 43, the end 50 forming a hook for engaging in the aperture 29' of the eye 29 on the splasher plate P. At its upper end, the hook shank is expanded to form a rectangular passage 44 for receiving a rectangular block 45 from whose opposite sides extend trunnion pins 46 and 47, respectively, these pins journaling in ears or walls 49 and 40 depending from the bottom 55 of the frame A below the front wall 33 thereof. The hook end 42 extends forwardly at right angles with the trunnion axis so that, when the hook structure is swung with the trunnion block, the hook end may enter or be withdrawn from the eye aperture 29'.

Secured in the trunnion block is a cross pin 60 51 whose ends engage the longitudinal slots

52 and 53 in the side walls of the expanded end of the hook structure so that the hook structure may shift longitudinally on the trunnion block as well as swing with the 70 block.

Extending from the front end of the piston rod 39 is a cable 54 which is guided around a pulley or sheave 55 mounted on the frame structure A and which extends downwardly from the sheave and is connected with the upper end of the hook structure as by means of an eye screw 56. Extending from the rear end of the piston rod is a cable 57 which passes around a sheave 58, then downwardly and around a sheave 59, and has its other end connected with the hook structure at the lower end thereof, as by means of an eye screw 60. With this arrangement, when the piston 38 travels forwardly in the cylinder, the hook structure moves downwardly, and at the same time the resulting pull on the cable 57 causes the hook to swing rearwardly. When the piston 38 moves rearwardly, the cable 54 is tensed and the cable 57 slackened, and as the hook is pulled upwardly it is swung by gravity back to the vertical position.

Referring to Figures 1 and 2, the boom 18 has been swung to carry the supporting structure A in the position for a drilling operation and the splasher plate P has been carried into proper position over the runner trough and above the tapping hole outlet. After a drilling operation, the boom is swung to carry the drilling apparatus and the supporting structure A away from the furnace but leaving the splasher plate P in position for the casting run. Referring to Figure 2, the full lines show the hook structure in position just after the splasher plate has been lowered into position over the runner trough. When the piston 38 continues forward travel in the cylinder, the hook structure will be lowered to carry its end 43 below the upper wall of the aperture 29' and the hook structure will then be swung back to the dotted line position away from the lugs 29 and the boom 100 105

means may be provided. As shown, brackets 61 and 62 are secured to the furnace and support a vertical wall 63 across their outer end against which the front wall 33 of the supporting structure A abuts, and a locking hook 64 is provided for straddling the walls 33 and 63 to thereby hold the supporting structure A and the boom in service position while the splasher plate is being set for service or 5 is being reengaged by the hook structure preparatory to removal, the locking hook 64 being controllable from a remote point by means of a suitable cable 65. The means for controlling the fluid flow to the cylinder 37 10 may also be located at some remote point.

I will now describe the drilling apparatus and its support and control. This apparatus is suspended from the boom 18, the support comprising a plate 66 having a web 67 extending downwardly therefrom between the side walls 31 and 32 of the supporting framework A for the splash plate P. The plate 66 is secured by means of bolts 68 extending upwardly through the boom 18, preferably outside of the webs of the channels 19. As will be explained more in detail later, it may be desirable to adjust the drilling mechanism vertically, and, depending upon the adjustment desired, one or more spacer plates 69 may be inserted between the plate or body 66 and the boom, the bolts 68 being of sufficient length to permit such insert. The bolts may also extend through the head 30 of the frame structure A to hold it in place on the boom, and, when the nuts 70 on the bolts are turned up tight, the frame structure A and the support body 66 will be rigidly secured to the boom.

Formed in the web 67 is a slot 71 forming 40 a guideway for a trolley or truck structure 72, the frame of this structure comprising side walls 73 and 74 engaging the opposite sides of the web 67 along the slot 71. Shafts or axles 75 supported by the side walls 73 and 74 journal rollers 76 for which the web wall forming a lower side of the slot 71 forms a rail, the rollers being shown as flanged at their ends for engaging in recesses 71' in the web, the rollers thus assisting in preventing 45 transverse displacement of the truck structure on the web.

The web 67 along the upper side of the slot 71 has teeth 77 for engagement by a gear pinion 78. On the truck structure 72 a shelf 79 is provided on one side which supports an electric driving motor 80 and a reduction gearing structure indicated by 81, one end of the reduction gearing train being connected with the shaft of the driving motor and the other end of the train supporting the drive pinion 78 so that, when the motor is run, the truck structure 72 will travel on the web 67 under guidance of the rollers 76 in the guideway 71. The lower end of the web 67 with 50 the guide channel therein is inclined down-

wardly, the angle of inclination being substantially or approximately the angle at which the opening through the tapping hole is to be made under ordinary conditions. The drilling apparatus is suspended from the truck structure 72 to be bodily shifted with the truck. The drill operating and controlling mechanism is supported in a frame structure 82, and secured to opposite sides of this frame structure are hanger plates 83 and 84 whose upper ends 85 and 86 are offset inwardly to receive between them the segmental shaped lower end 87 of the truck structure 72. A pivot bolt 88 extends through the wall sections 85 and 86 and through the truck 50 end 87 for rotational adjustment of the drill mechanism supporting frame 82, a lock bolt 89 extending through the slots 90 in the walls 85 and 86 serving to lock the frame 82 rigidly to the truck in adjusted position. To readily accomplish rotational adjustment of the frame 82, the segmental gear rack 91 is mounted on the wall section 85 concentric with the pivot bolt 88, a screw or worm gear 92 meshing with the gear rack and having 55 its shaft journaled in ribs 93 on the truck structure, the end 94 of the shaft being polygonal for reception of a crank for turning the worm gear for rotational or angular adjustment of the frame 82. It is evident that 60 a motor could be mounted on the truck to supply the necessary power for turning the worm gear. For guiding and indicating the angular adjustment of the frame 82, measurement markings 95 may be applied on the 65 segmental gear and indicating means, such as an arrow 96, applied on the truck.

The frame 82 has front and rear end walls 97 and 98, respectively, and an intermediate transverse wall 99. Extending between and 70 journaled in the walls 97 and 99 is a driving cylinder 100 through whose bore extends the drill spindle 101, the drive cylinder having spines 102 projecting into the bore for engagement in the channels 103 in the drill 75 spindle so that the spindle must rotate with the drive cylinder but may shift axially relative to the cylinder.

Projecting forwardly from the wall 99 above the drive cylinder is a shelf 104 on 80 which is mounted an electric driving motor 105 whose shaft is coupled to one end of a train or reduction gearing (not shown) within a casing 106 mounted on the shelf, the outgoing shaft 107 from the transmission gearing being journaled in the wall 97. Between the wall 97 and the reduction gearing train, a spur gear 108 is secured to the shaft 107 and meshes with a spur gear 109 secured to one end of the drive cylinder whereby, when 85 the motor 105 is operating, the drive cylinder 100 will be rotated to rotate the drill spindle.

The outer bearing end of the drive cylinder 100 extends through and beyond the wall 99 and has secured thereto a gear 110 which 90

meshes with a gear 111 on the front end of a countershaft 112 which is journaled in webs 113 and 114 between the bottom and side walls of the frame 82. Between the webs 5 the counter shaft carries a gear 115 which meshes with a gear 116 secured to the inner end of a screw shaft 117 which at its front end is journaled in the webs 113 and 114. The screw shaft extends rearwardly through the frame 82, its rear end being journaled in the rear wall 98 of the frame 82 and a thrust bearing 118 being interposed between the wall 98 and a collar or flange 119 on the screw shaft. The screw shaft has threaded 10 engagement with a block 120, which block or cross head is shifted as the screw shaft is turned and is guided by lower and upper guideways 121 and 122 formed in the frame 82. The cross head extends above the upper 15 guideway 122 and journals the end 101 of the drill spindle 101, flanges or collars 123 preventing longitudinal movement of the spindle relative to the cross head. The gearing train between the driving cylinder 100 and the screw shaft and the threading of the screw shaft are dimensioned so that the axial shift or feed of the drill spindle will be in proper accord with the turning of the 20 spindle and of the drill 124 connected with the spindle, the front end of the spindle having the socket 125 in which the drill end may be securely seated.

An automatic brake structure 128 of any suitable construction may be associated with 25 the motor 105 to brake and stop the motor as soon as current supply is withdrawn therefrom. A similar brake structure 129 may be provided for the motor 80 which controls the movement of the truck structure 72.

30 Describing now the operation, the apparatus not being in use, the boom 18 is swung around to support the apparatus away from the runner trough, the truck 72 being toward the outer end of its guideway so that the 35 drilling apparatus will be clear of the floor. To relieve the supporting structure A from unnecessary strain, the splash plate P should be lowered to rest on the floor. The runner trough and tapping hole are now unobstructed 40 for the application of a mud gun or other apparatus for filling the tapping hole with clay.

When the drilling apparatus is to be used 45 preparatory to another casting run, air is first admitted into the cylinder 37 for operation of the hook structure to engage with and elevate the splash plate P above the floor. The motor 24 is then started to cause swing of the boom 18 to align the supporting frame structure A above the runner trough and with its front wall 33 in abutment with the locking wall 63 on the furnace, the hook 64 being then dropped to securely lock the frame structure A in position. The air flow through the cylinder 37 is

then controlled for shift of the piston 38 for downward movement of the hook 36 to deposit the splash plate across the runner trough and to then swing the hook rearwardly to disengage from the plate.

70 By turning the worm gear 92, after first loosening the locking bolt 89, adjustment is made of the drill apparatus frame 82 for the proper angle of the drill and the lock bolt 89 is then tightened. The motor 80 is now operated to shift the trolley structure 72 downwardly in the guideway 71 to bring the point of the drill to the clay in the tapping hole and then when current is withdrawn from the motor 80, the electric brake 129 will lock the motor and consequently the truck structure 72 against movement. The motor 105 is now started for turning of the 75 drill spindle and drill and for forward feed thereof. The drill is preferably of the conveyor type so that it will carry the drillings out of the hole thereby avoiding the necessity of periodically removing the drill and blowing or otherwise cleaning out the drilling. The drill may be provided with a special detachable bit 200 (Fig. 4) for drilling through any skull which may have formed 80 at the end of the clay plug in the furnace.

85 If, after the drill spindle has been shifted forwardly the full distance, the hole has not been completed, the spindle is withdrawn and the truck structure 72 is shifted farther down and then the drill is again started to 90 finish the hole. After completion of the hole, the drill is withdrawn and the truck shifted rearwardly to raise the drill apparatus frame and drill end above the floor, and then, after releasing of the locking hook 64, the motor 24 is operated to cause the boom 18 to swing the entire apparatus back to one 95 side and away from the runner trough, the splash plate however remaining in position to receive the metal discharged from the furnace through the drilled hole and to deflect the metal back into the runner trough. 100

105 After removal of the drilling apparatus by the boom structure, the drill is withdrawn from the spindle and a poking bar 201 (Fig. 5) is substituted so that, should any object become lodged in the tapping hole, the apparatus can be again swung into position over the runner trough and the poking bar 110 inserted into the tapping hole to remove the obstruction. The truck 72 may be moved back and forth to move the poking bar back and forth until the obstruction is cleaned out of the tapping hole and the drill spindle may also be rotated at the same time, if necessary. After clearing of the hole the apparatus is then swung back away from the runner trough, and after a casting run, the mud gun is applied to replug the tapping hole. At the end of a casting run, the splash plate is reengaged by the hook 36 and swung back with the other apparatus 115 120 125 130

clear of the runner trough so that the operation of the mud gun will be unobstructed.

All these various operations may be controlled by one man at some safe point sufficiently remote from the furnace front and the runner trough and the hot metal. The various switches for controlling electrical circuits and valves for controlling the pressure fluid circuit may be conveniently mounted on an operating board 202 from which the operator may readily observe the functioning of the apparatus. Referring to Fig. 6, switches 203, 204 and 205 are diagrammatically illustrated for controlling the current flow from a supply circuit 206 to the motors 24, 80 and 105, respectively, and a suitable valve 207 is provided for adjusting the flow of fluid under pressure from a source 208 to the cylinder 37 to control the operation of the hook 36. All hazards are thus eliminated and the greatest degree of safety is assured.

When a furnace is new, its bottom is high, and in this case the angle of drilling is less, but as the furnace bottom floor rapidly wears down from abrasion of the iron flowing out of the furnace and from general wear, the angle of drilling must be changed to a steeper one in order to get the hole down lower in the furnace to the molten metal at the bottom of the furnace. The frame 67 for supporting the truck which carries the drilling apparatus is therefore adjustable vertically independently of the supporting frame work. A. If a lesser angle is desired for the drill, the nuts 70 on the bolts 68 are loosened so that the supporting body 66 may be adjusted downwardly and then the gap is filled up by one or more spacer plates and the nuts retightened. After lowering of the frame 67, the screw or worm gear 92 is operated for setting the frame 82 for the desired angle of the drill.

At some plants wide splasher plates are used and these plates might interfere with the drill. Under such conditions the splasher plate may be held suspended at a sufficient height above the runner trough so that it would not interfere with the drill and then, as soon as the hole has been made and the drill has been removed, the splasher plate may be quickly lowered into position. The space 44 and the slots 52 and 53 in the hook structure may be of sufficient vertical extent for raising of the plate by the hook for clearance of the drill.

I have shown a practical and efficient embodiment of the various features of my invention but I do not desire to be limited to the exact construction and arrangement and operation as shown and described, as changes and modifications may be made without departing from the scope of the invention as outlined in the appended claims.

I claim as my invention:

1. In drilling apparatus for drilling tapping holes for blast furnaces, the combination of a movable supporting structure, a carrier movable on said supporting structure, a drill frame supported by said carrier, a drill and driving means therefor on said drill frame, power means for moving said supporting structure for alignment of said drill frame relative to a hole to be tapped, and power means for moving said carrier on said supporting structure for adjustment of the drill relative to the hole to be drilled. 70

2. In apparatus for drilling tapping holes for blast furnaces, the combination of a supporting boom, a guide frame supported by said boom, a carrier shiftable on said guide frame, a drill and driving means therefor supported by said carrier, power means for swinging said boom for alignment of said drill relative to a hole to be drilled and power means for shifting said carrier on said guide frame for adjustment of said drill. 85

3. In tapping hole drilling apparatus, the combination of a supporting structure providing a guideway, a truck shiftable on said guideway, a drill structure carried by said truck, means whereby said drill structure is adjustable on said truck for adjustment in a vertical plane of a drill on said drill structure, and means for shifting said truck on said guideway for bodily shift of the drill structure toward and from a hole to be drilled. 90

4. In tapping hole drilling apparatus, the combination of a supporting structure, a guide frame supported by said structure, a carrier truck shiftable on said guide frame, a drill structure carried by said truck and supporting a drill and driving means therefor, means for vertically adjusting said guide frame on said guide structure for vertical adjustment of said drill structure, and means for angularly adjusting said drill frame on said carrier truck. 100

5. In tapping hole drilling apparatus, the combination of a supporting boom, a drill structure suspended from said boom and comprising a drill and driving means therefor, and power means for swinging said boom for alignment of said drill structure relative to a hole to be tapped. 115

6. In tapping hole drilling apparatus, the combination of a supporting boom, a guide frame suspended from said boom, a truck shiftable on said guideway, a drill structure carried by said truck and incorporating a drill and driving means therefor, power means for swinging said boom for alignment of said drill structure relative to a hole to be tapped, and power means for shifting said truck on said guideway for advancement or retraction of said drill structure relative to a tapping hole. 125

7. In tapping hole drilling apparatus, the

- combination of a movable support therefor, a carriage shiftable on said support, a drill structure supported by said carriage and incorporating a drill and driving means therefor, power means controllable from a remote point for moving said supporting structure to position the drill structure in front of a tapping hole, and driving means for said carriage controllable from a remote point for shifting said carriage for positioning of said drill structure to drilling position.
8. In tapping hole drilling apparatus, the combination of a movable support therefor, a carriage shiftable on said support, a drill structure supported by said carriage and incorporating a drill and driving means therefor, power means controllable from a remote point for moving said supporting structure to position the drill structure in front of a tapping hole, driving means for said carriage controllable from a remote point for shifting said carriage for positioning of said drill structure to drilling position, and means for adjusting the angularity of said drill.
- 25 9. In tapping hole drilling apparatus, the combination of a boom, a drill frame suspended from said boom, a rotatable and axially shiftable drill on said frame, driving means on said frame for controlling the rotational and axial movement of said drill, means for vertically adjusting said frame relative to said boom, and means for angularly adjusting said frame relative to said boom for the desired angular setting of said drill.
- 35 10. In combination, a blast furnace splash plate having an apertured lug thereon, a supporting structure, a hook structure, means supporting said hook structure on said supporting frame for longitudinal and rotational movement, a taut cable connected with the ends of said hook structure, guides for said cable, and means for shifting said cable, said cable when shifted in one direction first causing longitudinal movement of said hook and then swinging movement to free its end from the splash plate lug, and shift of said cable in the opposite direction causing first swing of said hook into engagement with said lug and then longitudinal movement of the hook to raise and support said plate.
- 45 11. The combination with a blast furnace splasher plate having an apertured lug, of a movable supporting structure, a hook member, means supporting said hook member on said supporting frame for longitudinal movement and swinging movement, a taut cable connecting with the ends of said hook member, guides for said cable, and means for shifting said cable, shift of said cable in one direction causing swing of said hook member out of said apertured lug, and shift of said cable in the other direction causing first swing of said hook member into engagement with said apertured lug and then longitudinal upward movement of the hook member
- for raising and suspending said plate, and means for moving said supporting frame for transporting the suspended plate.
12. The combination with a blast furnace having a tapping hole, a splasher plate for application in front of and above said tapping hole, said plate having a suspension lug thereon, a boom structure carrying a hook for engagement with said lug for supporting said plate, means for swinging said boom structure to carry said plate into position for service or for carrying said plate away from the furnace, and power driven means on said boom structure for operating said hook for suspension of said plate or for release therefrom.
- 70 13. The combination with a blast furnace having a tapping hole, a splasher plate for application in front of and above said tapping hole, said plate having a suspension lug thereon, a boom structure carrying a hook for engagement with said lug for supporting said plate, means for swinging said boom structure to carry said plate into position for service or for carrying said plate away from the furnace, and power driven means on said boom structure for operating said hook for suspension of said plate or for release therefrom, and locking means for locking said boom structure to the furnace wall during 85 operation of said hook to position said plate for service or for raising said plate preparatory to transportation away from said furnace.
- 90 14. In tapping hole drilling apparatus for blast furnaces, the combination of a supporting structure, an arm on said supporting structure, a splasher plate transporting hook on said arm, power means on said arm for raising and lowering said hook, a drill structure suspended from said supporting structure, power means for moving said supporting structure for carrying said drill structure and a supported splash plate to or away 95 from a tapping hole, and means for vertically adjusting said drilling structure.
- 100 15. In tapping hole drilling apparatus for blast furnaces, the combination of a boom, an arm on said boom, a hook supported by said arm for transportation of a splash plate, driving means on said arm for raising and lowering said hook, a guide frame supported by said boom, a truck shiftable on said guide frame, a drill structure carried by said truck and incorporating a drill and driving means therefor, means for vertically adjusting said guide frame relative to said boom, means for effecting angular adjustment of said drill frame relative to said truck, and power means for swinging said boom for the transportation of a splash plate and said drill structure to and from service position.
- 115 16. The combination with the splasher plate for a blast furnace of a carrier structure therefor, hoisting mechanism on said 120 125 130

carrier structure, and means controlled by the operation of said hoisting mechanism for automatically connecting itself with the splasher plate or for disconnecting itself 5 therefrom.

17. The combination with a splasher plate for a blast furnace, of a supporting boom, hoisting mechanism on said boom including a vertically movable hook, power 10 mechanism on said boom for operating said hoisting mechanism, and means operable during initial vertical movement of said hook for connecting said hook with said plate preparatory to suspension movement of said 15 plate or for release of said hook from said plate after said plate has been transported.

18. Tapping hole drilling apparatus for blast furnaces comprising a boom, a drill frame suspended from said boom, a drill and 20 driving means therefor on said frame, means for swinging said boom to align said drill frame relative to a tapping hole to be drilled, and means for effecting vertical and angular 25 adjustment of said drill frame relative to said boom for the desired angularity of drilling.

19. In apparatus for drilling tapping holes in blast furnaces, the combination of a supporting structure, a drill frame suspended 30 from said structure, a drill mounted on said frame, power means for moving said supporting structure for locating said drill frame for a drilling operation, and power driven means on said drill frame for causing rotary 35 and axial movement of said drill.

20. In apparatus for drilling tapping holes in blast furnaces, the combination of a supporting structure, a drill frame supported from said structure, a drill mounted on said 40 drill frame, power means for moving said supporting structure for locating said drill frame for a drilling operation, a driving motor on said drill frame, a transmission train between said motor and drill for rotating said 45 drill, and a transmission train between said motor and drill for axially moving said drill.

21. In apparatus for drilling tapping holes in blast furnaces, the combination of a supporting structure, a drill frame supported 50 from said structure, a drill spindle on said drill frame adapted to receive a drill, a motor on said drill frame, a transmission train between said motor and spindle for rotating the spindle, a screw on said drill frame, a 55 transmission train between said motor and screw for rotating said screw, and a connection between said spindle and screw for causing axial movement of said spindle when said screw is rotated.

60 22. In tapping hole drilling apparatus the combination of a supporting boom, a drill frame supported by said boom, a drill on

same frame adapted for rotation and for axial movement thereon, means for swinging said boom to align said frame with a hole to be tapped, a motor on said drill frame, and connections between said motor and drill for 70 causing combined rotary and axial movements of said drill.

23. In tapping hole drilling apparatus, the combination of a support, a drill frame carried by said support, a rotatable and axially 75 shiftable drill on said frame, driving means on said frame for controlling the rotational and axial movement of said drill, means for swinging said support to align said frame relative to a hole to be tapped, and means 80 for angularly adjusting said frame relative to said support for the desired angular setting of said drill.

24. In tapping hole drilling apparatus, the combination of a support, a truck shiftable 85 back and forth on said support, a drill frame pivoted on said truck to be rotatable in a vertical plane, a drill and driving means therefor on said frame, means for controlling the movement of said truck and means for 90 rotating said frame for alignment of said drill relative to a hole to be tapped.

25. The combination with a blast furnace having a tapping hole, a splasher plate for application in front of and above said tapping hole, a support for said plate, hoisting means on said support for controlling the vertical movement of said plate, and means for moving said support for locating said plate. 95

26. The combination with a blast furnace having a tapping hole, a splasher plate for application in front of and above said tapping hole, a movable support for said plate, hoisting mechanism on said support including a hook, means effective during initial movement of said hook by said hoisting mechanism automatically controlling the application of the hook to the plate or release therefrom, and means controlling the movement of said support for transporting the plates when suspended on said hook. 100

27. In combination, a splasher plate for a blast furnace, a movable support therefor, a hook suspended from said support for receiving said plate, and power means on said support for raising and lowering said hook. 115

28. In combination, a splasher plate for a blast furnace, a swinging boom, and power driven hoisting mechanism on said boom including a hook for engagement with said plate. 120

In testimony whereof I have hereunto subscribed my name at Gary, Lake County, Indiana. 125

AUGUST F. GIESE, JR.
